(57) **CLAIM**

The ornamental design for an apparatus for dispensing liquefied fluid, as shown and described.

DESCRIPTION

FIG. 1 is a front perspective view of an apparatus for dispensing liquefied fluid showing my new design;

FIG. 2 is a back perspective view thereof;

FIG. 3 is a back view thereof;

FIG. 4 is a front view thereof;

FIG. 5 is a side view thereof, the opposite side being a mirror image;

FIG. 6 is a top view thereof; and,

FIG. 7 is a bottom view thereof.

The broken lines shown in the figures are included for the purpose of illustrating the portions of the apparatus for dispensing liquefied fluid that form no part of the claimed design.

It is understood and reasonably inferred from the Figures, even in the absence of contour shading, that the depth of the inwardly curved portion in front diminishes gradually from the center front to the part lines without any other change or transition in shape in a manner at least partially illustrated by the profiles shown in FIGS. 1, 2, and 5. The surfaces of the claim otherwise follow the substantially cylindrical profile up to the height indicated by the solid lines.
